UNITED STATES PATENT OFFICE.

CHARLES W. LANGRIDGE, OF WYACONDA, MISSOURI.

PILE-TRUSS.

SPECIFICATION forming part of Letters Patent No. 691,392, dated January 21, 1902.

Application filed February 4, 1901. Serial No. 46,010. (No model.)

To all whom it may concern:

Be it known that I, CHARLES W. LANGRIDGE, a citizen of the United States, residing at Wyaconda, in the county of Clark, 5 State of Missouri, have invented certain new and useful Improvements in Trusses; and I do hereby declare the following to be a full, clear, and exact description of the invention, such as will enable others skilled in the art 10 to which it appertains to make and use the same.

This invention relates to trusses in general, and more particularly to trusses used in treating piles, the object of the invention being 15 to provide a simple, cheap, and efficient construction wherein a pneumatic pad will be held pressed with proper pressure against the affected parts to prevent them from protruding.

20 In the drawings forming a portion of this specification, and in which like numerals of reference indicate similar parts in the several views, Figure 1 is a perspective view showing the complete device. Fig. 2 is a section taken longitudinally through the pad. Fig. 25 3 is a section taken transversely through the pad.

Referring now to the drawings, the present truss comprises a belt 5, which is adapted to 30 be strapped around the waist of the wearer, and to this belt are connected two suspending straps 6 and 7 through the medium of short strap-sections 8, 9, 10, and 11, which are connected directly to the belt and have 35 buckles at their free ends for engagement with the ends of the straps 6 and 7. The straps 6 and 7 are adapted to lie with their central portions in close relation and with their end portions diverging upwardly, so that 40 the central portions may lie between the legs of the wearer.

The pad consists of a sleeve 15, which is 45 formed of a rubber sheet passed entirely around the straps at their central portions, and the ends of which sheet are overlapped and glued, the sleeve being likewise glued firmly to the straps. The overlapped portions of the sheet are on the underside of the straps and act to present a comparatively resistant 50 wall. In the upper side of the sleeve is formed an opening 16, and against the inner face of this upper side of the sleeve is glued

a piece of sheet-rubber 17, the edges of which are glued fast to the straps, so that between this piece 17 of rubber and the reinforced 55 lower wall of the sleeve there is formed an air-pocket, and when this air-pocket is filled with air under pressure it causes the rubber 17 to bulge out through the opening in the upper side of the sleeve to form the convex 60 portion of the pad. The straps are of elastic material, and by adjusting them through the buckles the proper position of the pad and the proper pressure thereof against the affected parts may be secured. 65

What is claimed is—

1. A truss comprising a belt, straps connected with the belt, an elastic sleeve inclosing the central portions of the straps and having an opening in the upper side thereof, and 70 an elastic sheet hermetically sealed over the opening at the inner side thereof and having its edges secured against the straps and the inner face of the sleeve and hermetically sealed to form an air-tight pocket, whereby 75 when air is admitted under pressure, the sheet will be projected above and through the sleeve.

2. A truss comprising a belt, straps connected to the belt and having their central 80 portions disposed side by side and in close relation, a sleeve encircling the central portions of the straps and consisting of a sheet of elastic material passed around the central portions of the straps and having its ends 85 overlapped against the under sides of the straps to reinforce the thickness of the sleeve, said sleeve having an opening in its upper side communicating with the interspace between the straps, and a sheet of elastic secured to the straps and sleeve against the inner face of the sleeve and covering the opening, the edges of said sheet being secured to form an air-holding chamber between it and the under side of the sleeve, 95 whereby when the chamber is inflated, the inner sheet will be forced through the opening of the sleeve.

In testimony whereof I hereunto set my hand in the presence of two witnesses.

CHARLES W. LANGRIDGE.
